TALKING MACHINE

Albert D. Philpot, Chicago, Ill.

Application June 12, 1931. Serial No. 543,890

13 Claims. (Cl. 274—17)

This invention relates to a talking machine and concerns itself with a structure that is adapted to be placed in the body of a doll for producing a talking doll. More specifically the invention concerns itself with a machine of this character which can be set in operation from without the body of the doll and which automatically stops when a record has been exhausted and which will elevate and return the stylus to its initial position without requiring any manual manipulation.

The invention comprises the novel structure and combination of parts hereinafter described and more particularly pointed out and defined in the appended claims.

In the accompanying drawings which illustrate a preferred form of this invention, and in which similar reference numerals refer to similar features in the different views:

Figure 1 is an elevational view of the talking machine in its uncased condition.

Figure 2 is a sectional view taken upon the line II—II of Figure 1 and illustrating parts in elevation.

Figure 3 is a sectional view taken upon the line III—III of Figure 2 upon an enlarged scale.

Figure 4 is an enlarged sectional view taken upon the lines IV—IV of Figure 1.

Figure 5 is an enlarged sectional view taken upon the line V—V of Figure 1 looking in the direction of the arrows.

Figure 6 is an enlarged sectional view taken upon the line VI—VI of Figure 1 looking in the direction of the arrows.

Figure 7 is a view very similar to Figure 2 illustrating parts in a different position.

Figure 8 is an enlarged sectional view taken upon the line VIII—VIII of Figure 1 looking in the direction of the arrows.

In describing the invention with reference to the drawings, it will be noted that the mechanism is supported by a pair of side plates 1 and a top plate 2 which bridges the side plates. In referring to Figure 3, it will be observed that a shaft 3 is journalled for rotation between the side plates 1. A spur gear 4 is keyed upon the shaft 3 adjacent one side plate. This gear 4 is adapted to be rotated by a reciprocating rack bar 5 which is slidably mounted in a guide casing 6 which may be secured or welded to the adjacent side wall 1.

A bearing strip 7 is preferably positioned in the top of the housing to form a good bearing surface for the top of the rack bar 5 during its reciprocating movement. The front end of the guide casing 6 terminates in a downwardly extending flange 8 which forms a shoulder that is

adapted to be engaged by a shoulder 9 (Figure 5) on the rack bar 5. It will be noted that the rack bar 5 terminates at its front end in a handle member of reduced portions whereby the shoulder 9 is formed. The handle portion of the rack bar 60 embodies a knob with a collar 5a which is adapted to abut the front end of the casing whereby the reciprocating movements of the rack bar 5 is limited to a predetermined movement.

Reverting to Figure 3 again it will be observed that a hub member 10 is keyed upon the shaft 3. This hub member 10 has a ribbon spring 11 secured thereto and wound thereon with the free end thereof anchored to a rod 12 that connects the side walls 1. It might be mentioned that this ribbon spring serves as a spring motor for actuating the driving mechanism as will later more fully appear. The hub 10 of the spring motor terminates in a flanged ratchet wheel 13. Adjacent the ratchet wheel 13 there is a large spur gear 14 which is loosely journalled upon the shaft 3 and is provided with a pawl 15 that engages the ratchet wheel 13. A spring 16 normally urges the pawl 15 into engagement with the ratchet wheel 13. The large spur gear 14 which is driven from the spring motor through the instrumentality of the ratchet wheel 13 and pawl 15 is adapted for driving a small spur gear 17 keyed upon a shaft 18 which is journalled between one of the side walls 1 and an L-shaped bracket 19 which is secured to the same side wall.

A spur gear 20 is secured upon the shaft 18 and this gear 20 meshes with a pinion 21 secured upon a shaft 22 journalled between the side walls 1. The shaft 22 carries a gear 23 which in turn carries a small pinion 24 secured upon a governor shaft 25 upon which a suitable governor 26 is mounted.

Reverting again to Figure 3, it will be seen that a sleeve member 27 is loosely journalled upon the shaft 3 adjacent the hub 10. This sleeve terminates in a pinion 28 which meshes with the spur gear 20 and is driven thereby relative to the shaft 3. The sleeve 27 which may be termed a sleeve shaft carries a record drum or cylinder 29 upon which a suitable record 30 may be carried.

The manner of supporting the stylus that operates with the record will now be explained. It will be observed that a cylindrical rod 31 extends inwardly from one side wall 1. A U-shaped member 32 is journalled upon the rod 31 by means of a pair of bearing lugs 33 which extend in parallel relation from one leg of the U-shaped member. A hangar 34 which is pro-

vided with a pair of parallel arms 35 terminating in pintle portions journalled in the arms of the U-shaped member 32 forms the stylus bar. The stylus bar 34 comprises a pair of forwardly extending arms 36 which approach each other at their outer ends and between the outer ends thereof, the holder 37 for the stylus pin 38 is pivotally mounted. In referring to Figure 7 which shows one of the arms 36 broken away, it will be noted that the holder 37 has a tail portion 37a which extends beyond the pivot 39 of the holder. This tail portion 37a extends between the two arms 36. A coil spring 40 connects the tail portion of the holder with an arm 41 extending outwardly from the U-shaped member 32. A vibration conducting wire or the like 42 also connects the tail of the holder 37 with a diaphragm 43 which is suitably mounted in a head 34 supported upon the top plate 2 of the frame of the machine.

The mechanism for elevating the stylus bar and returning the same to initial position as soon as a record has been played will now be set forth. With reference to Figure 3 it will be observed that a collar 45 is secured upon one end of the shaft 3 and this collar carries an arm 46 which terminates in a right angle portion 47 that extends over the peripheral face of the record drum. Referring to Figure 4, it will be seen that the portion 47 is in the form of a channel that slopes inwardly. The aforementioned stylus bar 34 has a depending lug 48 which is normally located in the path of movement of the arm portion 47. When the spring motor is wound up by pushing the rack bar 5 inwardly, the shaft 3 will be rotated and will rotate the arm 46 into the position shown in Figure 7. When the rack bar 5 is released and the record cylinder is rotated through the instrumentality of the spring motor, the shaft 3 will be rotated in a reverse direction until the arm 46 rotates to the position shown in Fig. 2, and this will occur when the stylus has traversed the complete cylinder. At this point the inclined portion 47 of the arm will engage the lug 48 and elevate the stylus bar from the record cylinder, and as soon as this stylus bar is elevated, it will slide along the inclined face of the portion 47 to the opposite side of the record cylinder, that is, to its initial starting position. To prevent the stylus from dropping off the outer edge of the record drum, a stop lug 49 has been stamped from the casing.

While it appears that the operation of the machine should be clearly understood from the foregoing description, a brief summary of the operation will be set forth. In its normal position, the motor is unwound and it is necessary to wind the spring 11 before it will operate. The spring motor is adapted to be wound up by pushing the rack bar 5 inwardly until the collar 5a strikes the casing, whereby the shaft 3 will be rotated for winding up the spring 11, and the arm 46 will be rotated to its starting position as shown in Fig. 7. During this operation, the ratchet wheel 13 will ride idly over the pawl 15 without rotating the gear 14. However, as soon as the inward pressure upon the rack bar 5 is released the spring motor will operate the gear 14 through the instrumentality of the pawl 15 and ratchet 13. The gear 14 will rotate the shaft 18 which is geared to the governor shaft as previously set forth and which is also geared to the record cylinder through the pinion 28 with the result that the record cylinder will be gradually rotated. As the record cylinder is gradually rotated, the

stylus pin will of course gradually traverse the same, and the arm 46 will gradually rotate with the shaft 3 as it is rotated by spring 11 in a direction reverse to that required to wind the same. Until it engages the lug 48 on the stylus bar and elevates the same and causes the same to slide over the sloping face on the angled portion 47 to its initial starting position. It will of course be understood that the U-shaped member 32 supports the stylus arm for rotatable and swinging movement in order that it may be actuated by the control arm 46 in the manner set forth. When the stylus has completely traversed the record cylinder the rack bar will of course have moved outwardly until the shoulder 9 engages the shoulder 8 on the casing to prevent further rotation. It will therefore be obvious that the reverse rotation of the shaft 3 will return the rack bar 5 outwardly into position for again winding up the spring motor.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In a machine of the character described, a record cylinder, a stylus cooperating therewith, a spring motor for operating said record cylinder, a control member for the stylus, means for winding up the spring motor and setting said stylus control and means for stopping said motor when said control disengages said stylus from the record cylinder.

2. In a machine of the character described, a shaft, a spring motor keyed upon said shaft, a record cylinder loosely journalled upon said shaft, gearing driven by said spring motor for rotating said record cylinder, a pinion keyed upon said shaft, a rack bar engaging said pinion and cooperating means between said rack bar and a stationary part of said machine for limiting said rack bar to a predetermined movement.

3. In a machine of the character described, a shaft, a spring motor keyed upon said shaft, a record cylinder loosely journalled upon said shaft, gearing operated by said spring motor for rotating said record cylinder, a gear upon said shaft, a guide housing in the plane of said gear, and a reciprocating rack bar mounted in said guide housing and engaging said gear, said rack bar and guide housing having cooperating shoulders for limiting the reciprocating movement of said rack bar to a predetermined extent.

4. In a machine of the class described, a shaft, a spring motor keyed upon said shaft, a record cylinder loosely journalled upon said shaft, a stylus for cooperating with said record cylinder, an arm keyed upon said shaft and having an inclined portion normally located over the periphery of said record cylinder for controlling said stylus, means for rotating said shaft a predetermined distance for winding up the spring motor and rotating said arm in a direction away from said stylus, said shaft being reversely rotated through the action of said motor for returning said control arm and elevating and shifting said stylus to its initial position.

5. In a machine of the character described, a record cylinder, a stylus for cooperating with said record cylinder, a spring motor for actuating said record cylinder, a control for the stylus, means for winding up the spring motor and setting said

stylus control for a predetermined range of movement during the rotation of said record cylinder for elevating said stylus and returning the same to initial position when the same has traversed the record cylinder.

6. In a machine of the character described, a shaft, a spring motor upon said shaft, a gear secured to said shaft, a rack bar for operating said gear for winding up the spring motor, a record cylinder loosely supported upon said shaft, a stylus for engaging said record cylinder, an arm rigidly secured to said shaft and having an inclined surface for elevating and shifting the stylus and means for limiting the reciprocating movements of said rack bar for limiting the rotation of said shaft to a predetermined extent.

7. In a machine of the class described, a record cylinder, a stylus cooperating therewith, a control member for said stylus, a spring motor, means for winding up said spring motor and moving said control away from said stylus, means for rotating said cylinder from said spring motor and moving said control toward said stylus for automatically disengaging the same from said record cylinder and shifting the same to initial position when the same has traversed said record cylinder.

8. In a machine of the class described, a shaft, a spring motor keyed to said shaft, a record cylinder loosely journalled upon said shaft, gearing connecting said spring motor and cylinder, a gear upon said shaft, a rack bar for operating said gear for winding said spring motor, a control for the stylus secured upon said shaft, and means for limiting the reciprocating movements of said rack bar.

9. In a machine of the class described, a shaft, a record cylinder loosely journalled upon said shaft, a gear keyed upon said shaft, a spring motor keyed upon said shaft, gearing connecting said spring motor and record cylinder, a stylus bar,

a control arm secured to said shaft, and a double shouldered rack bar for operating said gear and winding up said spring motor and rotating said arm in a direction away from said stylus.

10. In a machine of the class described, a record cylinder, means including a spring motor for operating said record cylinder, a stylus bar, a control therefor, means for winding up said spring motor and setting said control, said control being actuated thru the unwinding of said spring motor for elevating and shifting said stylus bar when said record cylinder has made a predetermined number of revolutions.

11. In a machine of the class described, a shaft, a spring motor secured upon said shaft, a gear upon said shaft, a reciprocable rack bar for engaging said gear, means for maintaining said rack bar constantly in engagement with said gear and means for limiting the reciprocating movements of said rack bar.

12. In a machine of the class described, a shaft, a spring motor secured upon said shaft, a gear secured upon said shaft, a reciprocable rack bar engaging said gear, said rack bar having spaced shoulders and means located between said spaced shoulders for limiting the movement of said rack bar to a predetermined extent in both directions.

13. In a machine of the class described, a shaft, a spring motor secured upon said shaft, a gear secured upon said shaft, a reciprocable rack bar engaging said gear, said rack bar having spaced shoulders, a stop member located between said shoulders for alternately engaging said shoulders and limiting the movement of said rack bar, a record driven by said spring motor, a stylus cooperating with said record and a control for said stylus having a limited range of movement and effective for elevating and returning the stylus to initial position as soon as said stylus has traversed said record.
